KNURLER MECHANISM FOR CIGAR MACHINES

Sigurd Clausen, Brooklyn, N. Y., assignor to International Cigar Machinery Company, a corporation of New Jersey

Application July 19, 1938, Serial No. 219,950

9 Claims. (Cl. 131—29)

This invention relates to cigar machines, especially to a cigar finishing unit, and more particularly to knurler operating mechanism for such a unit as that disclosed in the co-pending application of Henry H. Wheeler, Serial No. 189,300, upon certain features of which the present invention is to be regarded as an improvement or development.

In a cigar machine having such a unit, provision is made for knurling by movement of the knurler against an end of the cigar, both to locate the cigar and to knurl it. Inasmuch as the cigar can only be gripped lightly for the step of locating it for the operation of trimming and that of knurling, and since only a relatively small portion of the machine cycle of operation is thus used, it is frequently necessary to perform an added knurling operation by hand, because of the light and inadequate nature of the automatic knurling. In some instances, this mode of procedure necessitates the services of an inspector, with the undesirable and inordinate expense incidental thereto.

Under such conditions, to be explained hereinafter more at length, it is an object of the present invention to perform the same locating and knurling steps as those briefly indicated above, and also to add another knurling step in which the cigar, after it has been suitably located, is gripped more firmly and while so gripped is subjected to the knurling action of the knurler, which is given a further inward knurling movement for a longer period of time.

In further explanation of the above problem, it is to be noted that in a cigar machine characterized by such a finishing unit, after the wrapped cigar has been softened in the re-roller, it is delivered by the cradle of the latter to a finishing device provided with co-acting trimming knives and with grippers in which the cigar, thus located, has its tuck end trimmed to the required length, and its head end is smoothed by the same knurler which has first positioned the cigar axially.

To receive the cigar for trimming, the axial distance between the knurler and the trimmer, when not in operation, is greater than the length of the cigar, and therefore, upon delivery of the cigar into the gripper jaws, the knurler is advanced toward the cigar in such a manner as to place its head end into a predetermined axial position, and then the trimmer is moved into operating position against its tuck end.

Since relative motion between the cigar and the grippers takes place during this positioning

movement, the cigar holding jaws must be made to press only very lightly against the cigar to avoid bruising of the wrapper, but after positioning, they should preferably grip the cigar firmly to prevent damage from the turning action of the knurler. Furthermore, for locating the cigar, the clamps should press against the cigar only lightly, while for proper knurling, this clamping pressure should be increased slightly to prevent sliding of the cigar under a slight additional forward movement of the knurler. With previous mechanisms, only a small portion of the machine cycle is available for the knurling operation, making it necessary to resort to an additional hand knurling to finish the cigar. In the present mechanism, a separate cam is used for the knurler, so that a larger portion of the cycle can be utilized for the automatic knurling operation, and hand knurling may be eliminated from the regular routine. It may therefore, be desirable to provide two or more separate knurling operations by withdrawing and re-advancing the knurler a number of times while the cigar is firmly held in the grippers. It is the object of the present invention to provide a simple mechanism for performing the various motions to meet all of these different conditions.

In the accompanying drawing:

Fig. 1 is a view in sectional elevation of a knurler operating mechanism in the construction of which the present invention has been embodied;

Fig. 2 is a side elevation of the same, seen from the line 2—2 of Fig. 1, and

Fig. 3 is a view in side elevation of a modified form of cam.

Referring to the drawing, 11 is the housing frame of the re-rolling and trimming unit of a cigar machine, which supports the rolling drum 12 with its cradle 13, the knurler 14, the grippers 15 and 16, and the trimmer 17. The drum 12 is mounted on an oscillating shaft 28, the cradle 13 is resiliently supported and is adjustable for different thicknesses of cigars, and the trimmer 17 is axially movable through a sufficient distance to clear the cigar while being rolled and while it enters the grippers. The mechanism for operating the rolling drum 12, the cradle 13 and the trimmer 17 are shown and described in the aforesaid copending application #189,300, filed February 8, 1938, by H. H. Wheeler.

The knurler 14, which is attached to a horizontal shaft 18 slidable in bearings of frame 11, is actuated by a bell-crank lever 19 tensioned by a spring 20, the lever 19 carrying a roller 21

engaging with collars 22 on shaft 18. The lever 19 turns on a shaft 23 and is connected by a link 24 to a cam lever 25 fulcrumed on a shaft 26 and having a cam-follower roller 27 in engagement with a cam 29 on shaft 30. The roller 27 rests on the high portion of cam 29 (Fig. 1) while the cigar C is being rerolled by the drum 12. When the cigar is delivered into the gripper 15, the roller 27 descends the incline 31 of the cam, thereby permitting the spring 20 to advance 10 the knurler, which in position 14' (Fig. 2) contacts the cigar C and moves the same into the predetermined dotted position C' which is reached when the depressed portion 32 of the cam arrives under the roller 27. The latter remains on this cam portion while the trimmer is being moved from its inactive position 17' into its operating position 17 and while it is actuated to cut the cigar, whereupon the roller 27 runs off the cam portion 32 onto the portion 35, permitting the spring 20 to pull the lever 19 against a stop 33 (Fig. 2). The stop is so adjusted that the knurler is held by the spring against the head of the tightly-gripped cigar with just the proper pressure for perfect knurling.

The rotation of the knurler is produced by means shown in the copending application heretofore referred to. After completion of the knurling operation, the roller 27 ascends at 34 (Fig. 1) to the high portion 29 of the cam. If repeated knurling is desired, the low cam surface 35 may be subdivided by a hump or humps 35a as illustrated in Fig. 3, into two or more spaced surfaces, so that the knurler is temporarily withdrawn from the cigar while the roller 27 engages with any of these humps.

The lower grippers 15 are fixedly mounted on a shaft 36 supported in bearings on frame 11 and having an arm 37 connected by a link 38 to a cam lever 39 on shaft 26. The arm 37 is pulled by a spring 40 against an adjustable stop 41 which holds the grippers 15 in the proper position to receive the cigar from the cradle 13. The cam lever 39 carries a roller 42 following the periphery of a cam 43 mounted on the cam shaft 30 and having a hump 44. When the knurling operation controlled by cam 29 is completed, the hump 44 of cam 43 is designed to be engaged with roller 42, thereby lifting the arm 37 from the stop 41 and causing the gripper 15 to descend below the surface of the cradle 13 through openings 45 in the latter, thus discharging the finished cigar down the tail of the cradle.

The upper gripper 16 is loose on shaft 46 which has a crank arm 47 connected by a link 48 to a cam lever 49 on shaft 26. At one side of gripper 16 is fixedly mounted a collar 50 to which is attached a post 51 carrying a spring 52 anchored to a bracket 53 extending from the hub of gripper 16. At the other side of gripper 16, an arm 54 affixed to shaft 46 has a horizontal pin 55 extending into a space between the shank of gripper 16 and limit screw 56 carried by a projection 57 of the gripper hub. The lever 49 carries a cam-follower roller 58 held by a spring 59 against a cam 60 on shaft 30. As long as roller 58 engages the high portions 60 and 61 of cam 60, the weak spring 52 holds the gripper 16 against the pin 55 on arm 54 or against the cigar after the gripper has come down on it and has been lifted from the descending pin 55 by it, thus causing the gripper to exert only a light pressure on the cigar during the positioning stroke of the knurler 14. But, when the low portion 62 of cam 60 reaches the roller 58 after the positioning step,

the pin 55 engages the stop 56 and both springs 52 and 59 act upon the gripper 16, resulting in a strong gripping pressure during the ensuing knurling period, after which the incline 63 restores the roller 58 to the high position on cam 60, thereby lifting the gripper 16 from the cigar, ready to receive a new cigar after the completed cigar has been discharged by the recession of the lower gripper.

What is claimed is:

1. The novel method of fabricating a cigar which comprises the steps of softening and shaping a wrapped cigar by rolling the same, then transferring the wrapped and rolled cigar to a trimming position in a finishing device, trimming the tuck end of the cigar by a trimming means, maintaining said trimming means in trimmed position after the trimming operation to serve as an abutment for the trimmed end of the cigar, then advancing knurling means against the head end of the cigar a plurality of times while gripping the body of the cigar against turning thereof by the knurling means and discharging the cigar so rolled, trimmed and knurled.

2. In a cigar machine, the combination with a re-rolling device and a cigar holding concave constructed and arranged to cooperate therewith, of means disposed adjacent to the discharge end of said concave to receive said cigars serially and to apply a light gripping force to hold a cigar lightly whereby the cigar may be moved axially without damage thereto, a knurling means adapted to engage said cigar and move it axially to a predetermined position while applying to the head end a knurling force, said cigar holding means subsequently applying a firm gripping pressure to hold the cigar firmly in said position, said knurling means being adapted to move an added distance in knurling engagement with said cigar end axially of the cigar.

3. In a cigar machine, the combination with cigar supporting devices, including grippers for yieldingly engaging cigars fed thereto, of a locator means for locating cigars on said devices, means for moving said locator means to engage a cigar and position it in said grippers, means acting substantially coincidently therewith to operate said grippers to grip a cigar lightly while it is being located, and acting subsequently thereto for causing said gripper to firmly grip said cigar, trimming means for trimming each cigar to size while it is firmly gripped on said device, said locator means acting to move an added distance axially against said cigar end, while so held.

4. In a cigar machine, the combination with a re-rolling mechanism, and a cigar supporting concave cooperating therewith, of cigar supporting members located adjacent to said mechanism and arranged to receive cigars fed therefrom, means for locating cigars on said supports, means for lightly holding cigars in said members while their ends are being located, means for trimming an end of a cigar located on said supports, said cigar holding means acting to hold firmly each cigar during the operation of said trimming means, and said locating means applying knurling pressure to the head end of said cigar while the cut end abuts against the trimmer.

5. In a cigar machine, the combination with cigar supporting devices, of a knurler arranged adjacent to said devices, means for moving said knurler to locate each cigar axially on said devices and to knurl the head end of said cigar

lightly, means for holding said cigar lightly in said devices during said initial operation of said knurler while the cigar is moved to its axially located position, said cigar holding means acting subsequently for firmly gripping said cigar, and said knurler moving means applying added pressure to the knurler whereby it is advanced to complete a firmer knurling operation.

6. A knurler mechanism of the class described, having the features claimed in claim 5, in which spring devices are provided for actuating the several holding means and said knurler, and cam mechanism is provided to govern and synchronize the tensioned operations of said spring-activated holders and knurler respectively.

7. In a cigar machine, the combination with relatively movable cigar supports, and means for feeding cigars thereto serially, of means for moving said supports to and from each other to grip each cigar, said last-named means including a spring for effecting a light gripping action on a cigar positioned in said support for a part of the gripping operation, and for causing a firmer gripping force to be applied to said cigar for the remainder of said gripping operation, and cam means by which the co-operating mechanisms are synchronized through the several phases of their co-operative movements.

8. In a cigar machine of the class described, having a knurler device, relatively movable cigar

supports, means for feeding cigars thereto, and mechanism for moving said supports to and from each other to grip cigars, said mechanism including a first spring for applying to one of said supports a tension of predetermined value adapted to cause said support to approach toward the other, to embrace a cigar positioned in said supports with a variable gripping action, a second spring tensioned suitably for causing said knurler to apply pressure of a predetermined value to the end of the cigar for locating the same in said supports and for knurling, a cam shaft, and a set of cams thereon adapted for controlling the gripping of said supports, and for controlling their action to apply light gripping pressure during locating movement of the knurler, and also to advance the knurler a short distance while the cigar is more firmly gripped.

9. In a cigar machine having mechanism for performing a finishing operation, such as rerolling, upon a partly finished cigar, means to transfer said cigar to a knurling station and means to perform a plurality of knurling operations successively upon said cigar at said station, and at least one of said successive knurling operations being performed during a machine cycle subsequent to that in which said rerolling operation is performed.
